UNITED STATES PATENT OFFICE

93,350

DESIGN FOR AN AIR COMPRESSOR

Harley J. McAllister, Minneapolis, Minn.

Application June 13, 1934, Serial No. 52,167

Term of patent 7 years

To all whom it may concern:

Be it known that I, HARLEY J. McALLISTER, a citizen of the United States, residing at Minneapolis, in the county of Hennepin and State of Minnesota, have invented a new, original, and ornamental Design for an Air Compressor, of which the following is a specification, reference being had to the accompanying drawing, forming part thereof.

The single view of the drawing is a perspective of the air compressor, showing my new design.

I claim:

The ornamental design for an air compressor, as shown

HARLEY J. McALLISTER.
